[57] CLAIM

The ornamental design for a golf club head, as shown and described.

DESCRIPTION

FIG. 1 is a front view of a golf club head showing my new design.

FIG. 2 is a back view showing the design;

FIG. 3 is a top plan view showing the design;

FIG. 4 is an end view showing the design; and

FIG. 5 is a bottom view showing the design.

The characteristic feature of my design resides in the back of the club head.
